TO THE BRUNSWICK-BALKE-COLLENDER COMPANY, OF CHICAGO, ILLINOIS, A
CORPORATION OF DELAWARE.

BOWLING PIN.

Application filed June 5, 1922. Serial No. 565,964.

To all whom it may concern:

Be it known that we, JOSEPH W. BISHOP and JESSE O. MATTESON, citizens of the United States, residing at Muskegon, in the 5 county of Muskegon and State of Michigan, have invented certain new and useful Improvements in Bowling Pins, of which the following is a specification.

The object of this invention is to provide 10 a durable and substantial bowling pin which can be made to conform to standard regulations as to size, shape and weight, which will give a good ringing sound similar to solid wood pins and which will not crack, 15 split, or chip like a solid wood pin, or wear as quickly.

The invention also has for its object to provide a bowling pin having a hollow metal core with a composition covering thereon 20 and securely united therewith to answer all the requirements for a bowling pin as well as a solid wood pin and to give a more pleasing effect in bowling and greater life and service.

25 In the accompanying drawings we have illustrated a selected embodiment of the invention wherein—

Fig. 1 illustrates a pin with the covering removed from a part of the core;

30 Fig. 2 is a transverse sectional view on the line 2—2 of Fig. 1;

Figs. 3 and 4 illustrate different kinds of cores that may be used.

Referring to the drawings the core 5 is 35 preferably made in the general form of a bowling pin in two or more sections which may be cast but are preferably stamped, pressed or otherwise formed out of sheet metal and then united at their abutting edges 40 by welds 6 or in any other suitable way so that they will be held rigidly together. This core is made of a reduced size to receive the covering 7 of sufficient thickness to make the completed pin conform with standard

45 regulations as to size and shape. The pin may readily be made to conform also with standard regulations as to weight by varying the gauge of the sheet metal employed in making the core, or varying the thickness 50 of the covering or by adding additional covering material or increasing the density thereof. We may use a covering of plastic composition, vulcanized to the core and con-

sisting of a hard rubber compound, or a composition of hard vulcanized rubber having a fibrous material incorporated therewith, but we prefer to use a composition consisting of a plastic compound having small pieces of wood in the form of little sticks or splinters thoroughly incorporated there- 55 with, as shown in Fig. 1.

We have found in practice that the covering can be caused to adhere tightly to a core having a continuous and uninterrupted surface but bowling pins are subjected to very 60 rough usage and it is practically impossible to establish a standard test to which a pin may be subjected for determining its suitability to meet all conditions which may arise with, as shown in Fig. 1. 65

70 We have found in practice that the covering can be caused to adhere tightly to a core having a continuous and uninterrupted surface but bowling pins are subjected to very 75 rough usage and it is practically impossible to establish a standard test to which a pin may be subjected for determining its suitability to meet all conditions which may arise with, as shown in Fig. 1.

80 We have found in practice that the covering can be caused to adhere tightly to a core having a continuous and uninterrupted surface but bowling pins are subjected to very 85 rough usage and it is practically impossible to establish a standard test to which a pin may be subjected for determining its suitability to meet all conditions which may arise with, as shown in Fig. 1.

90 We have found in practice that the covering can be caused to adhere tightly to a core having a continuous and uninterrupted surface but bowling pins are subjected to very 95 rough usage and it is practically impossible to establish a standard test to which a pin may be subjected for determining its suitability to meet all conditions which may arise with, as shown in Fig. 1.

an anchor and interlocking engagement between the cover and the core. The core is provided with ordinary holes 8 which may be round, as shown, or any other suitable 5 shape, the sheet metal being cut out completely to form the holes. In Fig. 3 square holes are shown formed by punching the sheet metal outward to provide projections 9 which are embedded in the covering. In 10 Fig. 4 the sheet metal is punched outward to form round holes and projections 10 substantially similar to those shown in Fig. 3. The projections may not be as regularly formed as they are indicated in the drawings 15 but they will be stamped outward and, if desired, the metal may be first cut to make the projections extend from each side of a straight sided hole more or less as shown in Fig. 3 or around a circular hole more or 20 less as shown in Fig. 4, or the metal may simply be punched outward without previous cutting or slitting to form irregular projections which take their own form and shape as the metal gives away under the punching 25 operation. We prefer to bend the projections to hook form so that they will make interlocking engagement with the covering.

The impact of the ball is usually against the belly of the pin where it is thickest 30 and we prefer to insert a transverse brace 11 in the core at this point to make the pin better withstand the severe blows to which it is subjected, especially by large 35 balls. It may be said, in this connection, that if the core is dented or caved in, so to speak, even slightly, it will pull away from the covering in some cases and leave a space between the core and the covering, and if the covering of the pin is subjected 40 to a heavy blow opposite this space it will very likely break or crush or otherwise give way. We have experienced this in some of our tests but we have found that when the core is sufficiently rigid and the material 45 is securely united with or anchored to the core the pin will give superior and better service than a wood pin under as near as possible similar conditions. We prefer, however, to use a strengthening or 50 reinforcing brace or plate 11 which may be secured in the core in various ways. We have found it satisfactory to provide the core with a plurality of spaced slots 12 and the brace with a plurality of projections 13 55 to enter the slots 12. In assembling the members of the core and the brace the latter would be inserted in its proper position in one member and then the other member or members would be arranged in proper 60 position; to facilitate the assembly some of the projections would be provided with bevel edges 13' so that the core members may be easily assembled to their proper abutting position.

65 Our invention provides a hollow bowling

pin having a thin metal core with a covering of plastic material securely united therewith to form a pin of regulation size, shape and weight which will be more substantial and more durable than good quality wood pins used under similar conditions, which will give a good ringing sound and which will give satisfaction to the bowler and to the owner of the bowling alley. The base of a wood pin wears out more quickly, 70 under ordinary conditions, than any other part and the pins are often returned to provide them with suitable bases, and many efforts have been made, some more or less successful, to provide pins with detachable 75 and renewable bases. We have found in tests of our improved pin that the base stands up and maintains its shape and configuration very much longer than a wood pin so that returning or the use of detachable and renewable bases are unnecessary. Our pin presents a great advantage over 80 wood pins in this respect because the bowling alley proprietor is not able to repair pins with deformed bases when they should 85 be repaired and some times allows them to remain in use when they should not be used, often thereby affecting a player's score favorably or adversely. We have 90 found that our pin is far superior to a good 95 wood pin as regards wear of the base and this makes the pin more economical as a practical matter and more satisfactory to the bowler.

After wood pins have been used for some time the surface thereof becomes roughened and to some extent splintered and dented and otherwise defaced which makes them to that extent irregular in shape and somewhat reduced in diameter. This does not 100 improve the bowling game nor does it maintain the standard as to pins which is supposed to exist for good bowling. Furthermore it tends to interfere with the handling of the pins in pin setting machines 105 and particularly in automatic machines. We have found in actual practice that pins made in accordance with our invention as herein described will preserve their surface condition and dimensions much longer 110 than the best wood pins, thereby maintaining the standard requirements and facilitating the handling of pins in setting machines.

115 We are aware that the construction and arrangement of parts, composition of the covering, the gauge of the metal and other features of the invention may be varied to a more or less extent without departing from the spirit or sacrificing the advantages 120 of the invention and we reserve the right to make all such changes as fairly fall within the scope of the following claims:

125 We claim:

1. A bowling pin comprising an inner hol- 130

- low metal core, and an outer covering vulcanized on and securely united with the surface of the core.
2. A bowling pin comprising an inner hollow core having openings therein, and a composition covering on the core having portions thereof projecting into said openings to anchor the covering to the core.
3. A bowling pin comprising an inner hollow core having openings therein with outward projections at the edges of said openings, and a composition covering on said core and embedding said projections therein.
4. A bowling pin comprising an inner hollow metal core having straight sided openings therein with angular projections extending outward from the sides of the opening, and a composition covering enclosing the core and embedding said projections therein.
5. A bowling pin comprising an inner hollow core, a transverse plate arranged in the core to form a brace therefor, and a composition covering enclosing the core and secured thereto.
6. A bowling pin comprising a hollow metal core having spaced slots therein, a transverse brace arranged within the core and having projections engaging said slots, and a composition covering enclosing the core and secured thereto.
7. A bowling pin comprising a hollow metal core having openings therein, a transverse brace within the core, and a composition covering enclosing the core and secured thereto with portions thereof anchored in said openings.
8. A bowling pin comprising a hollow metal core having spaced holes and slots therein, a transverse brace engaged with said slots, and a composition covering enclosing the core and having portions thereof anchored in said openings.
9. A bowling pin comprising a hollow metal core having openings therein with outward projections at the edges of the openings, a transverse brace in the core, and a composition covering enclosing the core and embedding said projections.
10. A bowling pin comprising a hollow metal core, a transverse brace secured within the core about midway between the top and bottom of the belly of the pin, and a composition covering enclosing the core and secured to the surface thereof.
11. A bowling pin comprising a hollow metal core having openings therein and hook shaped projections extending outward from the edges of the openings, and a composition covering enclosing the core and embedding said projections.
12. A bowling pin comprising an inner hollow core having openings therein with projections at the edges of said openings, and a composition covering on said core and engaged with said projections.
13. A bowling pin comprising a hollow sheet metal core having openings therein, and a composition covering on said core and engaged with said openings.
14. A bowling pin comprising a hollow sheet metal core having openings therein and projections around said openings consisting of the metal displaced to form said openings, and a composition covering on said core and engaged with said openings and projections.
15. A bowling pin comprising a hollow sheet metal core, a sheet metal plate located transversely within the belly of the core and secured to the core to form a brace therefor, and a composition covering enclosing the core and secured thereto.

JOSEPH W. BISHOP.
JESSE O. MATTESON.
